IRVING R. ROWE, OF STONINGTON, CONNECTICUT, ASSIGNOR TO THE ATWOOD MACHINE COMPANY, OF STONINGTON, CONNECTICUT, A CORPORATION OF NEW JERSEY

SPINNING AND TWISTING MACHINE

Application filed October 4, 1930. Serial No. 486,339.

This invention relates to improvements in spinning and twisting machines and has for its object to provide a novel mechanism for driving a plurality of spindles disposed in rows on opposite sides of the machine, together with means for automatically keeping a predetermined tension on the driving belt without affecting the position of the belt with respect to the spindles actuated thereby.

Another object is to provide a driving and tension mechanism which is a complete and effective unit for a deck of spindles, so that several decks of spindles may be superposed in a frame, thereby minimizing the floor space occupied by the machine, increasing the utility and output of the machine, and facilitating ease and rapidity of removing and replacing the driving belt, when desired.

Another object is to provide a driving and tension mechanism adapted to be mounted in an auxiliary frame adjacent one end frame of the machine, thereby obviating the use of take-up idlers for the belt and affording a greater number of spindles to be banked together in a deck between the end frames of the machine.

Another object is to provide certain improvements in the form, construction and arrangement of the several parts, whereby the above named and other objects may effectively be attained.

A practical embodiment of my invention is represented in the accompanying drawings, in which

Fig. 1 represents a detail side elevation, partly in section, of one end of a spinning and twisting machine, having two decks of spindles superposed in a frame and my improved driving and tension mechanism applied to each deck;

Fig. 2 represents a horizontal section taken in the plane of the line II—II of Fig. 1, looking in the direction of the arrows; and

Fig. 3 represents a detail vertical section taken in the plane of the line III—III of Fig. 1, looking in the direction of the arrows;

In the drawings, I have illustrated the invention as applied to a spinning and twist-

ing machine having two decks of spindles superposed in a frame, each deck being provided with a separate driving and tension mechanism, forming a complete unit and, as each unit is similar, I deem it only necessary 55 to describe the mechanism included in a single unit.

The end frame of the machine is denoted by 1, and the upper and lower pairs of rods or pipes denoted by 2, 3, which are secured to 60 the end frames at 4, 5 respectively. The pairs of rods 2, 3 are disposed on opposite sides of the frame and extend throughout the length of the machine. It is to be understood that a similar end frame serves to support the opposite end of the several rods, etc.

An upright 6 is spaced from the end frame 1 and connected thereto by horizontally disposed rails 7, 8, 9, 10, of which one end of each rail is fixed to the upright 6, while the 70 other end is secured to the end frame 1. The rails are disposed horizontally in upper and lower pairs, of which the rails 7, 8 are substantially in alinement with the upper pairs of rods or pipes 2, 3 and the rails 9, 10 arranged to aline with the lower pairs of rods or pipes 2, 3.

A carrier is disposed between each pair of rails and arranged to slide lengthwise toward and away from the upright 6 and end frame 80 1. This carrier comprises a plate 11 having a shaft 12 journaled in bearings 13, 14 at one end of the plate and a shaft 15 mounted in bearings 16, 17 at the other end of the plate. The shaft 12 is provided on its outer ends 85 with anti-friction rollers 18, 19, while the shaft 15 carries pinions 20, 21.

Each pair of rails is formed with oppositely disposed upper flanges 22, 23 and oppositely arranged lower flanges 24, 25, between 90 which upper and lower flanges the rollers 18, 19 and pinions 20, 21 of the carrier move. The lower flanges are provided with racks 26, 27 which coact with the pinions 20, 21, respectively, which racks terminate in flat 95 portions 28, 29 for the rollers 18, 19, respectively, to travel on.

A motor 30 is suspended from the plate 11, by means of bolts 31 and its driving pulley 32 disposed above the plate 11 in position to 100

receive a driving belt 33. This belt 33 is arranged to pass through the end frame 1, around guide pulleys 34, 35 carried by suitable brackets fixed to the rods or pipes 2, 3, 5 respectively, and then lengthwise through the machine in position to frictionally engage the spindles 36, each of which is mounted in a bearing 37 carried by supports 38 secured to the rods or pipes 2, 3 by bolts 39. 10 In order to maintain the driving belt at a constant tension, the shaft 15 is extended outwardly so as to project through an elongated slot 40 in the rails 7, 9 in position to receive a counterbalance, in the present instance, in the 15 form of a pulley 41 provided with a strap 42, one end of which is fixed to the pulley 41, while the other end has a loop 43 arranged to receive a weight 44 which depends therefrom. It will be understood that the shaft 15 may also be extended through elongated 20 slots 45 in the rails 8, 10 and a similar pulley strap and counter-balance applied thereto so as to increase the tension on the belt if so desired. 25 From the foregoing it will be seen that a constant tension will be applied to the belt 33 through the weight 44 tending to exert its pressure on the pulley 41 through the strap 42 and hence to the shaft 15 which, in turn, 30 will transmit its rotary motion to the pinions 20, 21 which coact with the racks 26, 27, which serve as a means for pulling the carrier with its motor and driving pulley outwardly toward the upright 6, thereby automatically 35 removing all slack and maintaining an even tension on the belt.

It is obvious that various changes may be resorted to in the form, construction and arrangement of the several parts without departing from the spirit and scope of my invention; and hence, I do not intend to be limited to the details herein shown and described, except as they may be included in the claims.

45 What I claim is:

1. The combination with a spinning and twisting machine having an end frame and a spindle driving belt of an auxiliary frame secured to said end frame, longitudinal guide rails and racks on said auxiliary frame, a carrier having a shaft provided with pinions thereon arranged to coact with said racks, a motor and its driving pulley mounted on said carrier, and means carried by said shaft for actuating the pinions to move the carrier, motor and its driving pulley to adjust the tension of the belt.

2. The combination with a spinning and twisting machine having an end frame and 60 a spindle driving belt of an auxiliary frame secured to said end frame, longitudinal guide rails and racks on said auxiliary frame, a carrier having a shaft provided with pinions thereon arranged to coact with said racks, a motor and its driving pulley mounted

on said carrier, and a counterbalance carried by said shaft for actuating the pinions to move the carrier, motor and its driving pulley to adjust the tension of the belt.

3. The combination with a spinning and twisting machine having an end frame and a spindle driving belt of an auxiliary frame secured to said end frame, longitudinal guide rails and racks on said auxiliary frame, a carrier having anti-friction rollers slideable 70 on said guide rails, a shaft journaled in the carrier and provided with pinions arranged in position to coact with said racks, a motor and its driving pulley mounted on the carrier, and means carried by said shaft for actuating the pinions to move the carrier, motor and its driving pulley to adjust the 75 tension of the belt.

4. The combination with a spinning and twisting machine having an end frame and a spindle driving belt of an auxiliary frame secured to said end frame, longitudinal guide rails and racks on said auxiliary frame, a carrier having anti-friction rollers slideable 80 on said guide rails, a shaft journaled in the carrier and provided with pinions arranged in position to coact with said racks, a motor and its driving pulley mounted on the carrier, and a counterbalance carried by said shaft for actuating the pinions to move the carrier, 85 motor and its driving pulley to adjust the tension of the belt.

5. A belt tightener for twisting machines comprising a pulley, a motor connected with said pulley for driving the same, reciprocating means for supporting said motor and pulley, a bracket for supporting said reciprocating means, a rack positioned substantially parallel to said bracket and to the direction of movement of said reciprocating means, a rod carried by said reciprocating means a pinion mounted on said rod and continually meshing with said rack, and a weighted member acting on said pinion for giving the pinion a tendency to rotate whereby said reciprocating means will automatically move the motor and the pulley in a direction for causing tension to be brought to bear on a belt mounted on the pulley.

6. A belt tightener for twisting machines comprising a pulley, a motor connected with said pulley for driving it, reciprocating means for supporting said motor and pulley, a fixed rack positioned substantially parallel to the movement of said supporting means, a rotatable pinion carried by said supporting means and meshing with said rack, and means acting on said supporting means for normally giving the pinion a tendency to rotate whereby said reciprocating means will automatically move the motor and pulley in a direction for causing tension to be brought to bear on a belt mounted on the pulley.

7. A belt tightener for twisting machines

comprising a pulley, a motor connected with said pulley for driving it, reciprocating means for supporting said motor and pulley, a pair of fixed racks positioned substantially parallel to the movement of said supporting means, a rotatable pinion for each rack carried by said supporting means and meshing with said racks, and means acting on said supporting means for normally giving the pinions a tendency to rotate whereby said reciprocating means will automatically move the motor and pulley in a direction for causing tension to be brought to bear on a belt mounted on the pulley.

15. 8. A belt tightener comprising a driving pulley, a motor directly connected with said pulley, a reciprocating carriage supporting said motor, a bracket for supporting said carriage, a pinion rotatably mounted on said carriage, a rack meshing with said pinion, said rack being carried by said bracket, and means connecting said pinion whereby as the means moves in one direction said pinion will be rotated, and through the coaction of 20 said rack, said carriage and the parts carried thereby will be moved in one direction.

9. A belt tightener including a pulley, a motor directly connected with the pulley, a carriage supporting said motor, a pair of 25 brackets, means extending from the carriage resting on the brackets, a rack carried by each bracket, a pinion rotatably mounted on said carriage for each bracket, said pinions meshing with said racks, and means connecting 30 said pinions whereby as the means moves in one direction said pinions will be rotated and caused to move along said racks for shifting the position of said carriage, motor 35 and pulley.

40. 10. A belt tightener including a pair of supporting brackets, each bracket having a slot and a pair of parallel guiding auxiliary brackets forming a track, a stationary rack secured to each of said brackets, a carriage 45 having a plurality of traction wheels, said traction wheels being fitted into said tracks and guided thereby, said carriage having a rod extending through one of said slots, an electric motor carried by said carriage, a 50 driving pulley supported and driven by said motor, a pair of pinions mounted on said rod and meshing continually with said racks, and means for giving the pinions a tendency to rotate in one direction.

55. In testimony that I claim the foregoing as my invention, I have signed my name this 1st day of October, 1930.

IRVING R. ROWE.
